UNITED STATES PATENT OFFICE

FREDERICK J. RYAN, OF PHILADELPHIA, PENNSYLVANIA, ASSIGNOR TO F. J. RYAN AND COMPANY, OF PHILADELPHIA, PENNSYLVANIA, A CORPORATION OF DELAWARE

STACK CONTROL

Original application filed April 15, 1927, Serial No. 184,132. Divided and this application filed April 23, 1929. Serial No. 357,526.

This application is a division of my co-pending application, #184,132, filed April 15, 1927, for "means for and method of controlling furnaces", and is particularly concerned with the stack control illustrated therein.

It is necessary in furnaces of the fuel-fired type to employ vents through which the hot gases may pass outwardly, to provide room for the incoming fresh gas. These exhausted gases are usually passed outwardly through stacks, the size of which is sufficient to handle the maximum capacity of the furnace. Very seldom, however, is the furnace operated at its maximum capacity, so that during the ordinary operation, the vents are attempting to exhaust a greater volume of gases than that which is delivered in the ordinary manner into the furnace. This tendency of the vent or stack to exhaust more than a sufficient supply of gas is especially noticeable in a furnace employing an automatic control such as that illustrated in my copending application, in which is disclosed an equipment which functions automatically in turning on and off the supply of fuel and air to regulate the temperature. For example, a furnace employing a control according to my copending application may have been working at maximum capacity, approximately 3000 cubic feet of hot gases being vented per minute. If now, the furnace has reached a temperature of say 1650° F., the automatic control valve functions to prevent a temperature greater than that, accomplishing this result by cutting down the delivery of air and fuel approximately 30 to 40%. Assuming the reduction to be 30%, it can be readily seen that about 900 cubic feet of gases have been dropped from the total volume supplied. This diminution in quantity is practically instantaneous, and occurs at a time when the stacks are operating at full capacity.

If at this time, the furnace were tightly sealed up, with the exception of the suction passage, the velocity of gases passing outwardly through the stack would be immediately diminished greatly. What actually occurs, however, is that the velocity or

suction is still great enough to compensate for the pressure loss by drawing in excess air around the burner ports and through the cracks in the furnace walls. This action results in oxidation or scaling of the material to be treated, as well as the elements of the furnace, and at the same time reduces what I term the furnace pressure. By normal furnace pressure is meant that the percentage of hot gases within the heating chamber of industrial heating furnaces are at all times sufficient to prevent any uncontrolled intake of air into the furnace as a result of a low pressure area therein.

By my invention, the control system of my co-pending application is properly correlated with the stack control therein, so that upon diminution of the fuel and air supply to the furnace, a corresponding reduction in the effective stack opening will take place at the same time. By this means, since the total quantity of gases passed out through the stack per unit of time will be diminished, the pressure in the furnace will be maintained substantially constant, preferably at a slight excess of the critical or normal pressure previously referred to, so that there will be no tendency for decrease in the furnace pressure and consequent detrimental action of the incoming air on the material being treated.

An object of the invention, therefore, is to produce an efficient heat treatment of the material undergoing the treatment in a furnace.

Another object is to maintain a constant pressure in a furnace.

Another object is to arrange a stack control in a furnace in such manner as to maintain the pressure within the furnace substantially constant regardless of variations in the fuel and air supply thereto.

Another object is to produce a stack control for a furnace which is actuated simultaneously with a temperature-responsive means for maintaining the temperature in the furnace substantially constant, for maintaining the pressure conditions in the furnace substantially at a predetermined value.

Still another object is to device apparatus for a furnace for maintaining the pressure therein at a constant value, slightly in excess

of that required to prevent the entrance of air through uncontrolled openings into the furnace.

Yet another object is to prevent oxidization of the material being treated as well as the elements of a furnace, during the heat treatment of the said material in the furnace.

Other objects will appear hereinafter.

One form of my invention is shown in the accompanying drawings by way of illustration wherein,

Fig. 1 is an elevation showing the various inter-related connections to the furnace, which latter is shown in vertical section, while

Fig. 2 is an enlarged view of the control mechanism of Fig. 1.

In the drawings, a furnace 1 of conventional design is shown as having an inner chamber 2 and an outer enclosing furnace chamber 3. The outer chamber 3 is provided with a lower combustion portion 4 having an opening 5 for an oil burner 6 or other heating apparatus. The combustion chamber 4 extends into engagement with a hearth 7 which constitutes a bottom wall for the inner furnace chamber 2. The hearth may support, as shown, a material 8 which is to be treated. The upper walls 9 and 10 of the inner and outer furnace chambers 2 and 3, respectively, are provided with substantially aligned outlet openings 11 and 12 for the furnace gases. The outlet opening 12 for the outer furnace chamber 3 is extended by means of a stack 13 having therein a control valve 14, which is connected by linkage 15 to an air operated motor 16, the linkage 15 having a counterweighted lever 17 tending to hold the stack valve 14 in its normally closed position. The valve 14 may be so adjusted, however, as to insure a desired minimum passage of gases through the stack 13 from the furnace 1.

The burner 6, which may take the form of that disclosed in Patent #1,161,183, issued November 23, 1915, to George F. Beach, is connected by means of an oil feed line 18 to an oil valve 19 constituting one element of a valve group 20. The oil burner 6 is also connected by an air pipe 21 to an elongated casting 22 having a butterfly valve or similar mechanism 23 which constitutes another element of the valve group 20. The air motor 16 is connected by an air pipe 24 to a pilot valve 25 which constitutes still another element of the valve group 24. Air is supplied to the valve 25 by means of a supply pipe 26 leading to a main air supply pipe 27. One end of the pipe 27 may be connected to an air blower, (not shown) while the other end is connected to the casting 22. The valves 19, 23, and 25 may be operated by a mechanism such as the yoke-shaped member illustrated at 28, which is connected by means of a suitable armature 29 to a solenoid 30. The mechanism 28 is preferably provided with a plurality of

adjustable abutments 31 whereby desired ones, or all of said valves may be independently or simultaneously operated and adjusted.

The zero position of the air or butterfly valve 25, which may be indicated by an indicating plate 32, is preferably such that a minimum supply of air is continuously supplied to the oil burner 6, sufficient to maintain proper combustion conditions in the furnace 1, as well as the proper operation of the burner 6, when only the furnace losses are to be supplied. The oil valve 19 is also provided with by-pass means having a control element 33 whereby sufficient oil may be supplied to the burner 6 to compensate for furnace losses. Similarly, the closed position of the stack valve 15 is such that for the conditions just stated, sufficient draft is established to assure efficient operation of the furnace. The construction and arrangement of the parts 19 to 33 and 16 may be substantially as illustrated in the patent to Beach, No. 1,763,385 granted June 10, 1930, for valve apparatus, and more particularly as illustrated in Fig. 7 of said patent.

Since the specific structure of the various elements just enumerated forms no part of this invention except in the combination shown, no further description thereof is believed to be necessary.

The operation of the several parts of the valve group 20 from the no-load or furnace-heating position shown in the drawings in which the valves 23 and 19 are open to supply fuel and air and the valve 25 is closed so that no fluid pressure is supplied to the motor, to a load position in which the positions of these valves are reversed as shown in dotted lines in Fig. 2 may be effected by the energization of the solenoid 30, through an electrical control circuit 34 comprising a pair of conductors 35 and 36 extending from the solenoid 30 to an instrument panel 37. The panel 37 is also connected by leads 38 and 39 to a thermocouple or similar temperature measuring device 40, which preferably extends through a furnace wall 41, into engagement with the underside 42 of the hearth 7. The panel 37 is provided with temperature control apparatus 45 of conventional design which is responsive to variations in the leads 38 and 39 due to temperature variations in the thermocouple 40. A relay 46 is also provided for the connection and disconnection of the solenoid conductors 35 and 36 to and from the main supply circuit (not shown) in accordance with the operation of the temperature control instrument 45. The details of these instruments constitute no part of my present invention, and therefore, will not be further described or illustrated.

It is also to be noted that certain of the constructional features of the valve group 20 are not shown in detail, inasmuch as they are

embodied in the co-pending application of George F. Beach, #147,265, filed November 19, 1926, and assigned to F. J. Ryan and Company. It is further to be understood that the control apparatus above described is merely of conventional design and may be varied at will without departing from the essential features of my invention.

In operation, when the temperature control instrument 45 is adjusted to the value to which it is desired to heat the material 8, currents are supplied to the solenoid 30 through the conductors 35 and 36, causing the energization of the solenoid 30 and the actuation of the mechanism 28, the operation of which later results in the opening of the oil valve 19, the butterfly valve 23 and the pilot valve 25, the extent of opening in each instance being determined by the adjustment of the several abutments 31. Oil and air are now supplied to the burner 6 through the pipes 18 and 21, respectively, to the substantially full capacity of the furnace, while air is supplied to the air motor 16 to cause the opening of the stock valve 14. The increase in the amount of oil and air thus supplied to the burner 6, as well as the increase in the furnace provided through the opening of the stack valve 14, causes an increase in the temperature of the gases in the combustion chamber 4, these gases passing, as indicated, through the underside of the hearth 7, and finally discharging from the outer chamber 3 through the opening 12 and associated stack 13. The opening in the stack is now sufficiently great to permit substantially all of the exhaust gases to pass quickly therethrough.

When the temperature of the material 8 reaches and starts to exceed the desired value, the currents generated by the thermocouple 40, through the medium of the temperature control instrument 45 and the relay 46, cause the open-circuiting of the supply conductors 35 and 36 for the solenoid 30, and the consequent de-energization of the latter. The operating mechanism 28 now drops from its raised operating position to its original position, with the result that the oil valve 19, the butterfly valve 23, and the pilot valve 25 are closed, the first two valves remaining open sufficiently to supply the furnace losses. The pilot valve 25 is so constructed that when it closes, a relief port (not shown) is open, permitting the air in the pipe 24 to be discharged to atmosphere so that the counter-weighted lever 17 may drop and return to the stack valve 14 to its original position. By thus restoring the stack valve to an approximation of its original position, the escape of a sufficient quantity of exhaust gases to materially reduce the pressure within the furnace is prevented.

By reason of the furnace losses, the temperature of the combustion chamber 4 and

consequently that of the material 8 now drops below the predetermined value, whereupon the thermocouple 40, through the temperature control instrument 45 and relay 46, again effects the connection of the conductors 35 and 36 to their source of energy (not shown), and thereby causes the re-energization of the solenoid 30. The solenoid 30 again actuates the yoke-shaped mechanism 28 to lift it from its position shown in the drawings to its raised operating position, causing the opening of the oil valve 19, the butterfly valve 23, and pilot valve 25, and consequent increase in the temperature of the material 8 to the predetermined value. Thus the temperature of the material 8 is automatically maintained substantially constant. By so maintaining the pressure at a desired value, it is possible, as has been pointed out before, to prevent the entrance through uncontrolled orifices of any oxidizing atmosphere into the furnace interior, while by so maintaining the temperature of the material being treated and the pressure conditions within the furnace substantially constant, the product resulting from such treatment is particularly desirable, since it has been substantially unaffected by oxidizing gases playing thereover.

While the above description has dwelt almost entirely with the use of oil burners, it is obvious that the furnace might be adapted to employ coal or any other suitable type of fuel without departing from the essential features of my invention.

It is of course understood that the air motor 16 is shown merely for the purpose of illustrating one form of my invention, and may be varied at will, the connections between the motor and the valve being of any conventional form as may be the valve itself, and it is to be further understood that the invention is susceptible to numerous modifications and adaptations, it being intended that it be limited only by the scope of the appended claims.

I claim:

1. In a treating furnace, a treating chamber having an outlet stack, a damper in said stack, a fluid-pressure-operated motor to operate said damper and close the same upon admission of fluid pressure to the motor, air and fuel supply lines for said chamber, a fluid pressure supply line for said motor, valves in the air and fuel supply lines and normally open to supply air and fuel to the furnace, a normally closed valve in said fluid pressure supply line, a single member to reverse the positions of said valves and thermostatically controlled electrical means to operate said member.

2. In a treating furnace, a chamber having an outlet stack, a damper in said stack, a fluid-pressure-operated motor to operate said damper and close the same upon the

admission of fluid pressure to said motor, air and fuel supply lines for said chamber, a connection between the air supply line and said motor, a valve in the air supply line between the point of communication of said connection with the air supply line and the chamber, a valve in the fuel supply line, a valve in said connection, the last-named valves being disposed adjacent the valve of the air supply line, the valves of the air and fuel supply lines being normally open to supply air and fuel to the chamber to support combustion therein during a chamber-heating operation, the valve of said connection being normally closed, a single member having means to operatively engage all of said valves and reverse the positions thereof, and electro-magnetic thermostatically-controlled means for actuating said member.

FRÉDERICK J. RYAN.
